UNITED STATES PATENT OFFICE.

FRANK H. WARREN, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

TRIMMING MACHINE.

Application filed September 29, 1920. Serial No. 413,465.

To all whom it may concern:

Be it known that I, FRANK H. WARREN, a citizen of the United States, residing at Swampscott, in the county of Essex and State of Massachusetts, have invented certain new and useful Improvements in Trimming Machines; and I do hereby declare the following to be a full, clear, and exact description of the invention, such as will enable others skilled in the art to which it appertains to make and use the same.

The present invention relates to trimming machines for use in the manufacture of boots and shoes, and has special reference to such machines for trimming the projecting edges of the upper materials including the vamp and lining of a lasted shoe preliminary to the inseam sewing operation.

Commercial machines of this type are usually provided with a reciprocating trimming knife that works across a shearing face at one end of a guide roll, the other end of the guide roll being arranged to engage the sole of the shoe to act as a distance gage to determine the height of the trimming cut. The guide roll is driven and its peripheral surface is frusto-conical and knurled so that it may act to feed and guide the work and to turn up the projecting edges of the vamp and lining to present them to the trimming knives. With the use of this guide roll, however, it is necessary for the operator to exercise a high degree of care in order to guide and feed the work properly and also the roll is unable in many cases to act properly on the edges of the vamp and lining particularly at the tip of a pointed toe shoe. In applicant's co-pending application, filed of even date herewith, a machine is disclosed in which the guide roll is provided with a flange or button at its lower end to engage the root of the channel of the sole so that the roll may act as a combined channel guide to guide the work and a guide for presenting the projecting edges of the vamp and lining to the trimming means. On different classes of work, however, it is desirable to make the line of the trimming cut at different distances from the sole of the shoe and with the use of a guide roll acting as a distance gage to determine the height of the trimming cut, it is obvious that rolls of different heights

must be employed for the different classes of work.

The principal object of the present invention is to provide a machine for trimming the projecting edges of the vamp and lining of a lasted shoe preliminary to the inseam sewing operation that overcomes the disadvantages of the prior constructions, while retaining all of the advantages.

The illustrated construction comprises a novel combination consisting of trimming means and a channel guide, the trimming means including a driven roll and a reciprocating knife arranged to cooperate with a shearing action, and the channel guide being arranged to guide the upper material to the periphery of the shearing roll while bearing in the channel to regulate the closeness of trimming.

The less erect portions of the material to be trimmed first engage the channel guide, which is in advance of the shearing roll, and are thereby turned or bent up from the sole far enough to insure their engaging the periphery of the shearing roll instead of passing under the roll, and as they continue to move ahead they are deflected into the field of trimming by the periphery of the roll. Thus, the less erect portions pass through two successive stages of erection leading to the field of trimming. Preferably this channel guide is constructed and arranged to turn up and present the projecting edges of the vamp and lining to the trimming means and is adapted to facilitate trimming around the toe of a pointed shoe.

Other features of the present invention consist in certain constructions, arrangements and combinations of parts hereinafter described and claimed, the advantages of which will be obvious to those skilled in the art.

The several features of the present invention will be clearly understood from the following description and accompanying drawings, in which:

Figure 1 is a right side elevation of a portion of the head of a trimming machine embodying the features in their preferred form; Fig. 2 is a rear elevation of a portion of the machine illustrated in Fig. 1; Fig. 3 is a detailed sectional plan view of a por-

tion of the operating instrumentalities of the machine; and Fig. 4 is a left side elevation of a portion of the machine illustrated in Fig. 1.

5 The machine illustrated in the drawings is provided with a trimming knife 2 and a knife guard 4. The trimming knife is reciprocated in a circular path about a pivot 6 and the knife guard is formed on a block 10 secured by a screw 10 to the frame of the machine. The trimming knife works across a shearing face 12 at the upper end of a guide roll 14 carried by a driven shaft 16. The peripheral surface of the guide roll is 15 frusto-conical and is spirally milled or knurled.

The illustrated machine is also provided with a plow shaped finger 17 formed on a block 18 and arranged to engage the insole 20 and the vamp. The block 18 is secured by a bolt 20 and a tongue and groove connection to a bar 22 that projects forwardly at right angles from a block 24. The block 24 is secured by a bolt 26 and a tongue and 25 groove connection to a block 28 which, in turn, is secured by the bolt 10 and a tongue and groove connection to the knife guard block 8.

The guide roll 14 is the same as the guide rolls that are usually employed on this type of trimming machine, except that it is of less height. The finger 17 is arranged to engage the insole and vamp adjacent to and in advance of the roll 14, and projects below the bottom of the roll to regulate the closeness of trimming. Its tip is shaped to enter and conform to the channel of the insole and is therefore adapted to guide the shoe by engagement with the root of the channel flap. 30 Above the tip the finger is shaped to deflect inclined portions of the vamp nearly if not quite to the upright position they are required to assume when they reach the roll 14. Thus the finger 17 acts in various ways 35 to steady and guide the body of the shoe while guiding the upstanding marginal portion of the vamp to the roll and evening wavy or irregular formations thereof. This is especially advantageous when working 40 around the toe where the wavy formations 45 are more numerous and more marked.

It has been found in trimming machines of this type employing a guide roll which serves as a distance gage, that the upward 50 pressure of the work places a severe strain upon the bearings of the shaft and roll and that the shaft and bearings soon become worn. In the present machine, however, the finger 17 relieves the shaft and bearings 55 from the upward pressure of the work.

In order to vary the height of the trimming cut, the finger 17 may be adjusted vertically and within limits determined by a slot 60 through which the screw 10 extends.

65 The finger 17 also has provision for adjust-

ment in a direction longitudinally of the channel and transversely of the channel to vary the amount that the edges of the vamp and lining are raised, these adjustments being effected by means of the bolts 20 and 26 70 which extend through elongated slots 32 and 34 in the blocks 18 and 24, respectively.

While it is preferred to employ the specific construction and arrangement of parts illustrated and described, it is to be understood that this construction and arrangement is not essential except so far as specified in the claims, and may be changed or modified without departing from the broader features of the invention.

The nature and scope of the present invention having been indicated, and a machine embodying the several features of the invention in their preferred form having been specifically described, what is claimed is:

1. A shoe-trimming machine comprising means for trimming surplus material from the marginal portion of the upper on the bottom of a lasted shoe, a roll arranged to engage the channel flap of the sole, and a gage formed and arranged to project into the channel of the sole to turn up the channel flap into engagement with said roll and to regulate the closeness of trimming.

2. A shoe-trimming machine comprising means for trimming surplus material from the marginal portion of the upper on the bottom of a lasted shoe, said means including a roll arranged to engage the inner side of the material to be trimmed, and means arranged to engage the sole and said material in advance of said roll to regulate the closeness of trimming and to guide said material to said roll.

3. A shoe-trimming machine comprising means for trimming surplus material from the marginal portion of the upper on the bottom of a lasted shoe, said means including a roll arranged to run on the inner side of the channel flap of the sole, and means formed and arranged to turn up the channel flap in advance of said roll and to guide said marginal portion of the upper to the field of trimming.

4. A shoe-trimming machine comprising means arranged to trim surplus material from the marginal portion of the vamp standing up from the sole of a lasted shoe, said means including a shearing roll, and means formed and arranged to erect such parts of said marginal portion as are initially inclined toward the middle of the sole and to guide them to the periphery of said roll.

5. A trimming machine for use in the manufacture of boots and shoes having, in combination, a guide roll having a shearing face at one end and its other end directed toward the sole of a lasted shoe placed in

the machine, a trimming knife working across said shearing face to cooperate therewith to trim the projecting edge of the vamp of the shoe, and a distance gage formed and arranged to determine the height of the trimming cut and to deflect the margin of the vamp toward the periphery of the guide roll.

6. A shoe-trimming machine comprising means arranged to trim surplus material from the marginal portion of the vamp standing up from the sole of a lasted shoe, said means including a shearing roll, and a channel-guide formed and arranged to guide said marginal portion to the periphery of said roll while bearing in the channel to regulate the closeness of trimming.

7. A shoe-trimming machine comprising means arranged to trim surplus material from the marginal portion of the vamp standing up from the sole of a lasted shoe, and a member arranged to engage said marginal portion in advance of said trimming means to turn up partially the less erect portions of said surplus material, said trimming means including a member formed and arranged to complete the turning up of said less erect portions.

8. A shoe-trimming machine comprising cooperative shearing members arranged to trim surplus material from the marginal portion of the vamp standing up from the bottom of a lasted shoe, one of said members having a surface leading to the field of trimming to deflect such surplus material to said field, and a member formed and arranged to turn up less erect portions of said surplus material sufficiently to insure their deflection by said surface into the field of trimming.

9. A shoe-trimming machine comprising three members, two of which are arranged and operated to trim surplus material from the marginal portion of the vamp standing up from the bottom of a lasted shoe, and two of which are formed and arranged to turn up, in two successive stages, the less erect portions of said surplus material.

10. A shoe-trimming machine comprising means arranged to trim surplus material from the marginal portion of the vamp standing up from the sole of a lasted shoe, said means including a shearing roll, and a channel-guide arranged to turn up the channel-flap of the sole to run on the periphery of said roll and to maintain said channel-flap out of the field of trimming.

11. A shoe-trimming machine comprising cooperative shearing members arranged to trim the projecting edge of the vamp of a lasted shoe, one of said members being a roll arranged so that its periphery will run on the inner surface of the vamp, and a member having a work-engaging surface constantly adjacent to said periphery to guide the vamp to the latter.

12. A shoe-trimming machine comprising cooperative shearing members arranged to trim the projecting edge of the vamp of a lasted shoe, one of said members being a roll arranged so that its periphery will run on the inner surface of the vamp, and a member having a work-engaging surface tangential to said periphery to guide the vamp to the latter, said member being formed to engage the sole of the shoe so as to determine the height of the trimming cut while guiding the vamp as aforesaid.

FRANK H. WARREN.
